UNITED STATES PATENT OFFICE.

HENRY DOYLE, OF NEW YORK, N. Y.

DESIGN FOR A CALENDAR.

SPECIFICATION forming part of Design No. 35,943, dated June 10, 1902.

Application filed April 1, 1902. Serial No. 100,983. Term of patent 3½ years.

To all whom it may concern:

Be it known that I, HENRY DOYLE, a citizen of the United States, residing in New York, borough of Manhattan, and State of New York, have invented and produced a new and original Design for Calendars; of which the following is a specification.

This invention relates to a design for calendars, which is clearly shown in the accompanying drawings, in which—

Figure 1 is front elevation of the calendar, showing my new design; and Fig. 2 is a side elevation of the same.

Similar letters of reference indicate corresponding parts.

The leading features of my design consist of a panel *a*, representing a door as being composed of boards. Said panel is suitably grained to imitate wood, and the panel is provided with hinge-straps *b* *b'* at one edge and an escutcheon *b*² at the opposite edge. The door

thus represented is ornamented by a centrally-arranged inverted horseshoe *c*, and disposed around the horseshoe is a rabbit's foot *d* at one side, a four-leafed clover *e* laterally 25 above, and a wishbone *f* laterally below the same. At one lower corner this ornamental panel is provided with the calendar-pad *g*, and the suspension-chain is attached to the upper edge thereof.

Having thus described my invention, I claim as new and desire to secure by Letters Patent—

The design for a calendar as herein shown and described.

In testimony that I claim the foregoing as my invention I have signed my name in presence of two subscribing witnesses.

HENRY DOYLE.

Witnesses:

MARGARET P. POTTER,
HENRY SUHRBIER.
